UNITED STATES PATENT OFFICE.

HARRY H. GRIGGS, OF CLEVELAND, OHIO.

TRAFFIC SIGNAL.

Application filed March 12, 1925. Serial No. 14,892.

To all whom it may concern:

Be it known that I, HARRY H. GRIGGS, a citizen of the United States, residing at Cleveland, in the county of Cuyahoga and 5 State of Ohio, have invented certain new and useful Improvements in Traffic Signals, of which the following is a specification.

My invention is an improvement in traffic signals and more particularly of the type 10 operated manually.

An important object of my invention is to provide an illuminated safety platform for pedestrians when crossing the street, day or night, through heavy traffic either when the 15 officer is in charge or is off duty.

Another object of my invention is the provision of a signal which is clearly visible during the day or at night.

Another object of my invention is to provide 20 an illuminated traffic signal device.

Another object is to provide protection for the operator of the signal from rain or sun and to provide sufficient illumination to clearly outline the operator's figure during 25 the day or night.

Another object is to enable the operator to be in a comfortable position to operate the device without being exposed to contact with wet streets and roads.

30 Other objects and advantages will become apparent as the description of my invention progresses.

In the drawing forming a part of this specification and in which like numerals are 35 employed to designate like parts throughout the same,—

Fig. 1 is a side elevation of one form of the signal and support;

Fig. 2 is a side elevation of the signal and 40 support taken at right angles to Fig. 1;

Fig. 3 is a longitudinal section taken on line 3—3 of Fig. 1;

Fig. 4 is a cross section taken on line 4—4 of Fig. 1;

45 Fig. 5 is a top plan view of the invention; and

Fig. 6 is a top plan view of a second embodiment thereof.

Fig. 7 is a detail view of the shutter.

50 In the drawings Figs. 1 to 5 showing the preferred embodiment of my invention, I provide a safety platform or base 5 of sufficient area to permit the traffic officer or operator of the signal and others to stand comfortably thereon. The platform is sufficiently elevated from the street or road sur-

face to present a dry surface on which to stand.

A standard 6, secured at its lower end to the platform 5 extends upwardly to a 60 height considerably above the operator's head so that the signal device carried on the upper end of the standard will be in a line of clear vision to oncoming traffic.

The standard is preferably formed of a 65 hollow pipe through which a shaft 7 extends from above. This shaft extends within the standard to a point about midway thereof and is provided with an operating handle 8 which is screwed or otherwise secured to the shaft. This handle projects approximately at right angles to the shaft through an opening 9 in the standard. The opening 9 is of limited length and thereby limits the swinging of the handle 8 to about 70 a quarter of a turn.

On the upper end of the shaft 7, I have secured a signal device which is pyramidal in shape, the apex being secured to the shaft 7 to revolve therewith when the handle 8 is 75 moved.

The signal device consists of a pyramidal body portion 10 having four sloping sides A, B, C and D provided with depending flange sections *a*, *b*, *c*, and *d* respectively. 80 Two of the oppositely sloping sides A and B, are intended to bear the legend "Stop" in white letters on a red back-ground to indicate to traffic approaching the signal that traffic is proceeding across the street and 85 that traffic in the street should stop. The oppositely sloping sides C and D are intended to bear the legend "Go" indicating that traffic approaching these sides may proceed. In this instance the legend "Go" is displayed in blue letters while the back-ground is 90 white. The flanges *a*, *b*, *c* and *d* include a blue back-ground carrying certain legends as "Cross street safety platform", "No left turn", "Safety first", or the like in which the 95 letters are white.

Electric lights 11 are provided in the upper portion of the signal body to illuminate the signal and also to throw light rays down upon the officer or pedestrians. 100

Lights 12 are provided on the flange portions *a*, *b*, *c* and *d* which also serve to illuminate the signal and officer at night.

The sloping sides of the signal may be of transparent colored substances such as isinglass, celluloid or glass including the legends above referred to. Or, if desired, the 110

sides may be of opaque substance except for the legends carried thereby which may be stamped from the substance forming the side portions. In this event, the opaque 5 substance would be painted in the colors outlined above while some of the stamped-out sections could be covered with a transparent colored plate.

Suitable electric connections may be 10 made connecting the lights to a source of power, the feed wires being preferably carried within the standard 6. A lock switch 13 is provided so that the lights may be extinguished by the officer by inserting a key 15 therein. This type of switch is employed to prevent extinguishing of the lights by unauthorized persons.

Whenever the traffic officer is absent, day 20 or night, a drop shutter 14 cuts out the words "Stop" and "Go" making them invisible and leaving only the plain red or white upper part illuminated, and the lower blue section with white lettering "Cross street"—"Safety platform" also illuminated. 25 The shutter 14 is raised and lowered by means of a toothed link or rod 15 which has a gripping ring 16 attached to one end and is attached at the other end to an extension 30 17 on the shutter 14. By pulling on the ring 16 the shutter may be raised and by engaging one of the teeth on the rod 15 with the edge of the opening through which the rod passes, the shutter may be adjusted to any desired position or may be entirely 35 closed. The shutter 14 also serves to prevent snow or sleet from obscuring the legends either when the shutter is raised or lowered.

It will be seen, therefore, that I have provided 40 a portable traffic signal device in which the signals may be easily displayed during the day as well as at night and that sufficient illumination is directed toward the operator of the device so that his figure will 45 be properly outlined day or night.

It will be seen that the shape of the signal device provides a means of shelter for the officer against the elements such as rain, snow or sun.

50 It is also apparent that the platform will provide an illuminated safety platform for persons caught in the middle of the street during a change in traffic direction or when the officer is off duty.

55 Fig. 6 illustrates a second embodiment of my invention in which a conical signal device is adapted to be secured to the shaft 7 and to rotate therewith similar to the signal shown in Fig. 3. In this form of 60 my invention the signal is made up of sections A, B, C and D on which legends may be painted or stamped out as desired. The

combination of color and materials used in the form shown in Fig. 6 are similar to those described above in connection with Figs. 1 65 to 5.

In Fig. 6 I also show a sectional flange a, b, c and d depending from the sections A, B, C and D, respectively, of the conical signal. 70

Various changes may be made in the construction of the invention without departing from the spirit of the invention or the scope of the following claims.

I claim:—

1. In a traffic signal, a safety platform, a signal device rotatably mounted above the platform, and means for rotating said signal device, said signal comprising an umbrella-like body of transparent material 80 having legends thereon of contrasting color, and shutter devices hingedly carried by the signal device to cover the legends thereon.

2. In a traffic signal, a safety platform, a signal device rotatably mounted above the 85 platform, and means for rotating said signal device, said signal comprising an umbrella-like body of transparent material having legends thereon of contrasting color, and shutter devices carried by the signal device 90 to cover the legends thereon, said shutter devices comprising hinged cover plates, and operating handles projecting through the body portion of the signal device.

3. In a traffic signal, a safety platform, a signal device rotatably mounted above the platform, and means for rotating said signal device, said signal comprising an umbrella-like body of transparent material 95 having legends thereon of contrasting color, and shutter devices carried by the signal device to cover the legends thereon, said shutter devices comprising hinged cover plates, and operating handles projecting 100 through the body portion of the signal device, said operating handles consisting of toothed bars for engaging the signal device body portion to maintain the shutter in a predetermined position.

4. In a traffic signal, a safety platform, 110 a signal device rotatably mounted above the platform, and means for rotating said signal device, said signal comprising an umbrella-like body of transparent material having legends thereon of contrasting color, and shutter devices carried by the signal device to cover the legends thereon, said shutter devices comprising hinged cover plates, and means for adjusting said 115 cover plates in any one of a plurality of 120 open positions.

In testimony whereof I hereunto affix my signature this 10th day of March, 1925.

HARRY H. GRIGGS.
